UNITED STATES PATENT OFFICE.

JOHN T. CORBETT, OF AURORA, ILLINOIS.

FEEDING FUEL.

SPECIFICATION forming part of Letters Patent No. 340,101, dated April 20, 1886.

Application filed December 10, 1885. Serial No. 185,924. (No model.)

To all whom it may concern:

Be it known that I, JOHN T. CORBETT, of Aurora, in the county of Kane and State of Illinois, have invented certain new and useful Improvements in Feeding Fuel to Furnaces; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention is a further improvement on that shown in my Patent No. 329,890, dated November 10, 1885; and it relates to a novel construction and location of the magazine and its combination with other parts.

Figure 1 is a cross-section through the boiler, magazine, and fire-pot; Fig. 2, a vertical longitudinal section.

A is the structure for supporting the boiler and its appurtenances, and which may be of brick, masonry, iron, or other appropriate material; B, the horizontal boiler inclosed within such structure or furnace; C, the hollow fire-pot having a large water-space, c'; D, the magazine.

Instead of having the magazine extend directly through the boiler, as in my above-named patent, it extends upward outside of the boiler, thus permitting that portion of the space inside the boiler, which in that patent was occupied by the magazine, to be filled 35 with flues.

I prefer to make the magazine in two parts, as shown, one part being on one side of the boiler and one on the opposite side. In some cases, however, it may be single, extending up 40 at one side only of the boiler; or there may, if desired, be two such magazines on each side of the boiler, but all of course communicating with or leading the fuel down to the fire-pot.

45 The fire-box and its connection with the boiler constitute the subject-matter of another and independent application, and I therefore do not claim them in the present application, but describe them sufficiently to make clear

the present invention. I prefer to use a hollow water-holding fire-pot, c', indicating the water-space, and E E representing pipes which connect such water-space with the boiler. The water-pot may be circular or of any other suitable shape, as preferred. The magazine D, 55 it will be observed, conforms at its lower portion substantially to the curve of the boiler, and is in near proximity, if not in contact, with its exterior. This insures a very material utilization of heat.

The general arrangements of the structure as a whole, with the exception of the water fire-pot and the outside magazine, are substantially the same as those in my above-named patent.

F is the free passage or flue beneath the boiler; G, the lower set of boiler-flues; H, the upper set of boiler-flues; I, the gate or partition in the stack; J, the arrows showing the route of travel of the heated products of combustion, as in my said former patent—namely, first beneath the boiler from front to rear, next through the lower boiler-flues from rear to front, and finally through the upper boiler-flues from front to rear, and so into the smoke-stack.

K indicates a steam-pipe for conveying steam to any point where it may be needed for use.

L is an apparatus connecting the door M of the ash-pit with a steam-valve, for opening this 80 door more or less or for closing it by the agency of the steam, to vary the draft automatically, as needed.

I claim—

1. In a horizontal boiler, a fuel-magazine 85 not only communicating directly with the fire-pot, but also curving upward therefrom around and in near proximity to the boiler near its front, substantially as and for the purposes set forth.

2. In combination with a horizontal cylindrical boiler having a fuel-magazine extending upward in curves in close proximity to the outside of the boiler and near its front, the described system of passages serving to convey hot air first beneath the boiler from front to rear, next through the lower boiler-flues from rear to front, and finally through the up- 90 95

per boiler-flues from front to rear directly into the smoke-stack.

3. In combination, the horizontal boiler, the fuel-magazine communicating directly with the fire-pot and curving upward therefrom in near proximity to the curve or periphery of the boiler, as set forth, the heat-passage F, parti-

tion I, lower set, G, and upper set, H, of boiler-flues, and smoke-stack J, these parts being arranged and operating as set forth.

JOHN T. CORBETT.
